UNITED STATES PATENT OFFICE

146,971

DESIGN FOR A VACUUM CLEANER CASING

Henry A. Kroenlein, Jackson, Mich.

Application February 2, 1946, Serial No. 126,212

Term of patent 7 years

(Cl. D9—2)

To all whom it may concern:

Be it known that I, Henry A. Kroenlein, a citizen of Germany, residing at Jackson, in the county of Jackson and State of Michigan, have invented a new, original, and ornamental Design for a Vacuum Cleaner Casing, of which the following is a specification, reference being had to the accompanying drawing, forming part thereof.

In the drawing,

Fig. 1 is a top plan view,

Fig. 2 is a side elevational view,

Fig. 3 is a front perspective view of a vacuum cleaner casing showing my new design, the opposite side presenting substantially the same appearance as the side shown in Fig. 2; and

Fig. 4 is an end elevational view of the end opposite that shown in Fig. 3.

I claim:

The ornamental design for a vacuum cleaner casing, substantially as shown and described.

HENRY A. KROENLEIN.
